UNITED STATES PATENT OFFICE.

FRANK B. ALLEN, OF ELYRIA, OHIO, ASSIGNOR TO THE DEAN ELECTRIC COMPANY, OF ELYRIA, OHIO, A CORPORATION OF OHIO.

TELEPHONE SYSTEM.

999,728.

Specification of Letters Patent.

Patented Aug. 8, 1911.

Application filed November 29, 1909. Serial No. 530,449.

To all whom it may concern:

Be it known that I, FRANK B. ALLEN, a citizen of the United States, residing at Elyria, in the county of Lorain and State 5 of Ohio, have invented certain new and useful Improvements in Telephone Systems; and I do hereby declare the following to be a full, clear, and exact description of the invention, such as will enable others skilled 10 in the art to which it appertains to make and use the same.

My invention relates to telephone systems, and more particularly to trunk circuits which are intended to connect telephone lines 15 terminating at different exchanges, together, in circuits adapted for the carrying on of conversation between the connected stations. Circuits of this general nature are now well known in the art and are extensively used. 20 In their use several operations are required, among them the connections between the trunk circuit proper, the other central station appliances, and the line wires. To facilitate these connections, it is necessary to 25 signal the parties participating in them, and considerable apparatus is required to control the signals used. In the circuits now in use it is customary to speak of the exchange at the call-initiating line as the A 30 exchange, and the terminal at that end as the outgoing terminal of the trunk. The exchange at the other end of the trunk is called the B operator's position, and the terminal there, the incoming terminal.

35 The object of my invention is to produce a trunk circuit embodying a complete set of signals controlled for guiding the operators in making the connections. Among other things, I produce apparatus for signaling 40 the called or desired subscriber which is dependent upon the connections at both ends of the trunk circuit. To accomplish this I provide a device governed over an electric circuit, which is in turn controlled by a 45 trunk relay which is connected to one end of the trunk, and a terminal relay connected to the other end. Each relay is governed by the switching means at the end of the trunk to which it is connected.

50 My invention will be best understood by reference to the following description when taken in connection with the accompanying illustrations showing specific embodiments thereof, while its scope will be more particularly pointed out in the appended claims.

Figure 1 is a diagram of a telephone system showing two subscribers' lines, a central cord circuit and a trunk circuit according to my invention. Fig. 2 is a modification of the trunk circuit of Fig. 1. 60

Referring now to the drawings and the embodiments of my invention shown therein, in the upper left hand corner of Fig. 1 I show a diagram of a subscriber's line upon which is the station of a single subscriber at A¹. This includes the telephone transmitter T, the receiver O, the bell Y and condenser K⁴ in bridge of the line. The line extends to multiple jacks at the A or main exchange station. The line and 70 cut-off relays are shown at R¹ and R. The line lamp at L. At A I show a 3-conductor cord circuit terminating at P and P¹, although I may use any other well known form of cord circuit. The connections of 75 the cord circuit are separated by condensers K and K¹ interposed in the strands thereof. The tip supervisory relays are shown at R² and R³. The sleeve supervisory relays at R⁴ and R⁵. At Z and Z¹ I show retardation coils adapted to choke out the variations in the battery current, also the talking current. The supervisory lamps are shown at L¹ and L². At J¹, located in proximity to the plug P¹ at the A station, 80 I show the terminal jack of the trunk circuit which leads to the B station. At the B position the trunk is divided into two sections which are conductively separate but inductively united by the induction coils I 85 and I¹. Between the windings of these induction coils are interposed the condensers K² and K³. At R⁶ I show a relay controlled over the A end of the trunk and known as the trunk relay. At X I show a high non-inductive resistance which is normally in circuit with this relay but adapted to be shunted out. At R⁷ I show a relay which is controlled over the called subscriber's line and which is known as the subscriber's relay. At R⁸ I show a relay having certain functions hereafter to be described, and which is known as the control relay. This relay is self-locking. At R⁹ I show a relay which is controlled from the B end of 100 the trunk and which is known as the terminal relay. At R¹⁰ I show a relay controlling the connection of the signaling current to the line and which is known as the signaling relay. At L⁴ I show a signal which 105 110

is known as a guard signal and which also performs the function of a disconnect signal; that is, it indicates in its guard capacity to the B operator the fact that the plug 5 P^1 has been inserted into the jack J^1 , in its disconnect capacity, that said plug has been withdrawn from said jack. At L^3 I show a signal which indicates the combination 10 of the appliances for signaling the called subscriber, and is known as the ringing lamp. At N , N^1 , N^2 and N^3 I show the ringing keys, and at Q the master key. M , M^1 , M^2 and M^3 are the sources of 15 signaling current. At the right of the figure 15 I show a subscriber's line upon which there are four stations, C, D, E and F, which are provided with the usual substation apparatus and which have signals adapted to answer to current of a frequency different 20 from that to which each of the others responds. This line terminates at the B operator's position in multiple jacks J^2 which are accessible to the B operator. R^{11} and R^{12} are the cut-off and line relays 25 respectively on this line. L^5 is a line lamp. At the B board the trunk terminates in the plug P^2 , which is adapted to be inserted into the jacks of the called subscriber's line.

The operation of my invention, which will 30 best serve to describe the functions of the various pieces of apparatus, is as follows: Assuming that the subscriber at station A^1 desires to communicate with the subscriber at station C, the subscriber at A^1 removes 35 the receiver O from the hook H which rises to close the switch 1—H. This completes a circuit through the relay R^1 as follows: negative side of battery B^7 — R^1 —2—3—4—H—1—T— the Wheatstone bridge at A^1 —5— 40 6—7—8— to positive side of battery B^7 . Condenser K^4 in the bell bridge at the substation prevented the operation of the relay R^1 before the removal of the receiver. The relay R^1 pulls up the armature 9 closing the 45 switch 9—10, lighting the lamp L over the following circuit: negative side of battery B^7 —9—10—L—11— to positive side of battery. The lamp L is before the A operator, and on observing its illumination, she inserts 50 the plug P into the line jack J of the calling subscriber. The circuit is immediately completed through the sleeve supervisory relay R^4 and the line relay R as follows: ground G^1 —battery B^1 —12— R^4 —13—14—15—R— 55 8— to ground at G. The relay R is energized, pulling up the armatures 3 and 6 cutting off the calling line through the line relay and extinguishing the lamp L. The relay R^4 pulls up the armature 16, closing 60 the switch 16—17 in the circuit of the lamp L^1 . This lamp is not lighted, however, as simultaneous with the energization of relay R^4 , a circuit is closed through R^2 as follows: positive side of B^1 —18— R^2 —19—tip side, 65 of cord 20—21—22—5—substation appa-

ratus at A—4—23—24—25—26—Z—12— back to battery B^1 . The relay R^2 pulls up its armature 27 interrupting the circuit of the lamp L^1 at 27—28, and preventing the illumination of said lamp. The A operator 70 now connects her telephone set (not shown) in circuit with the substation and ascertains that the subscriber at the substation C is wanted. She then calls and communicates that fact to the B operator over a separate 75 order wire circuit. The B operator informs the A operator of the trunk which is to be used, in this case the trunk W which is shown in the drawing. The A operator, who usually is waiting with the plug in her 80 hand, immediately inserts the plug P^1 into the jack J^1 on this trunk. A circuit is completed through the relay R^5 as follows: ground G^1 —battery B^1 —12—30— R^5 —31—32—33—34— to ground at G^3 . The relay 85 R^5 pulls up its armatures 35 and 36 cutting off the test at 37, closing the circuit of the lamp L^2 at 35—38 and the circuit of the relay R^3 at 36—39. The lamp L^2 is immediately lighted over the following circuit: 90 positive pole of battery B^1 —18— L^2 —40—41—42—38—35—30—12— to negative pole of B^1 . A circuit is also completed through the tip supervisory relay R^3 and the trunk relay R^6 , the latter at the B exchange. This 95 circuit is traced as follows: positive pole of B^1 —18— R^3 —43—39—36—44—45—46—47—48—I—X— R^6 —49—I¹—50—51—52—53—Z¹—12— to negative pole of battery B^1 . The current in this circuit is sufficient to 100 energize the trunk relay R^6 , but owing to the resistance X, is insufficient to operate the relay R^3 . The relay R^6 pulls up armature 54, engaging its front contact 55 and completing a circuit through the guard lamp L^4 105 and the trunk relay R^6 as follows: G^4 — B^3 —54—55—56—57—58— L^4 — to ground at G^{11} . The lamp L^4 lights up and in its guarding capacity indicates to the B operator that the plug P^1 is inserted in the jack of the trunk W. The B operator, then, after testing the called line and finding it idle, inserts the plug P^2 into the jack J^2 of that line. The circuit through the relays R^9 and R^{11} is completed as follows: ground at G^7 — B^5 — R^9 —60—61—62— R^{11} —117—63— to ground at G^{14} . R^{11} pulls up its armatures 64 and 65, cutting off the called line from the line relay and signal. The relay R^9 pulls up the armature 58, interrupting the circuit of the guard lamp L^4 and extinguishing the same. The armature 58 is drawn up to engage the front contact 59 in the second circuit of this lamp to be described presently. The armature 66 is attracted, interrupting the test at 67 and closing the switch 66—68. The armature 69 is attracted, closing the switch 69—70 in the circuit of the relay R^8 . 120

The B operator now closes the switch N of the generator M which we will assume is 130

adapted to furnish current of a character to which the bell at substation C responds. In this act the master spring Q is closed to engage the contacts 71 and 72. A circuit is thus closed through the relay R⁸ as follows: ground G¹⁰—72—Q—71—73—R⁸—74—70—69—75—76—77—battery B⁴—to ground G⁶. This energizes the relay R⁸ which pulls up armature 78, closing the switch 78—79 and locking itself on the following circuit: G⁹—79—78—R⁸—74—70—69—75—76—77—B⁴—G⁶. The lamp L³ is illuminated by current over the following circuit: G⁸—B²—L³—78—79—G⁹. This lamp serves as a ringing lamp; that is, it is illuminated during the stage between the first application of the ringing current and the response of the called subscriber to indicate to the B operator that the called station has not yet responded. The relay R⁸ also attracts its armature 82 closing the contacts in the circuit of the relay R¹⁰ which is now energized over the following circuit: ground G¹⁰—72—Q—R¹⁰—80—81—82—83—56—55—54—B³—to ground at G⁴. This circuit, it will be seen, is directly controlled by the relay R⁸ which operates the switch 54—55 therein. This circuit is also controlled by the relay R⁹ acting through the relay R⁸. The relay R¹⁰ pulls up the armatures 84 and 85 to engage their front contacts 86 and 87. Signaling now takes place through the following circuit: ground G¹³—machine M—N—90—87—85—88—89—91—93—condenser K⁶ and bell Y¹ of the station C—92—94—95—96—84—86—to ground G¹². This circuit will be made each time the ringing switch N and master key Q are operated. When the subscriber at station C responds by removing the receiver O¹ from the hook H¹, a low resistance bridge through the substation apparatus is completed and the subscriber's relay R⁷ energized over the following circuit: G⁵—one winding of R⁷—97—68—66—98—99—100—84—96—95—94—92—the substation apparatus—93—91—89—88—85—101—102—103—lower winding of R⁷—B⁴—ground G⁶. The relay R⁷ pulls up the armature 104, closing the switch 104—105 and completing a shunt 106 around the resistance. The resistance X being thus removed from the circuit of the relay R³, the current flow therein is sufficient to energize R³ which pulls up its armature 41 breaking the circuit of the supervisory lamp L² at 40—41. The extinction of this signal indicates to the A operator that the called station has answered. Relay R⁷ also attracts the armature 77 breaking the circuit of relay R⁸ at 76—77. This relay being de-energized, releases the armatures 78 and 82, the former interrupting the circuit of the lamp L³ and indicating to the B operator the response of the called subscriber. The interruption of the switch 81—82 breaks the

circuit of relay R¹⁰, preventing the reapplication of the ringing current to the line and the objectionable ringing in the called subscriber's ear. The subscribers at A¹ and C now converse over the following circuit: 70 from the transmitter T—1—H—4—23—24—25—K¹—53—52—51—50 through the induction coils I¹ and I—102—101—85—88—89—91—93—H¹—T¹—O¹—92—94—95—96—84—100—99—induction 75 coils I and I¹—48—47—46—45—K—20—21—22—5—receiver O— and back to T. Current is supplied to one side of this circuit by battery B¹ and to the other by battery B⁴ through the connections which are 80 readily apparent without description. Upon the termination of the conversation each subscriber hangs up his receiver. The breaking of the switch 1—H at substation A¹ interrupts the circuit of relay R² which 85 has been described, allowing the armature 27 to fall back, closing the switch 27—28 in the circuit of the lamp L¹ which now lights up. Upon observing this, the A operator pulls out plug P, restoring the apparatus at 90 the answering end of the cord to normal condition. The interruption of the hook switch at station C breaks the circuit of relay R⁷ which becomes inert. The switch 104—105 in the shunt of X is interrupted 95 placing the resistance again in the path of the current through relay R³ and reducing the current therein to an amount insufficient to operate said relay. The armature 41 falls back, closing the circuit of the lamp L² 100 which lights up. The A operator now pulls out plug P¹ restoring the apparatus in the calling end of the cord to normal condition and breaking the circuit of the trunk relay R⁶. The armature 54 falls back upon the 105 contact 110, completing the following circuit: G⁴—L³—54—110—111—59—58—L⁴—G¹¹. This lights the lamp L⁴ which serving in its disconnect capacity, indicates to the B operator the disconnection of plug P¹ from 110 jack J¹. The B operator now pulls out plug P² which interrupts the circuit of the relays R⁹ and R¹¹, restoring the system to normal condition.

In Fig. 2 I show a slight modification in 115 which the application of the ringing current, after the first operation, is done automatically. I show an interrupter connected in a ground leg 121 which terminates in a back contact 120 of the master key spring 120 Q. When it is desired to ring the called substation, the ringing key is depressed and locked down. After the energizations of relays R⁶ and R⁸ have taken place, as described above, the master spring Q drops 125 back upon the contact 120 and a circuit through relay R¹⁰ is completed as follows: G¹⁶—V—121—120—R¹⁰—80—81—82—83—56—55—54—battery B³—ground G⁴. The interrupter V which is constantly rotating, 130

is constructed to complete this circuit through certain intervals only; consequently, the circuit just traced will be made for a certain period of time and then broken for a certain period of time during each revolution of the interrupter. This continues until the called subscriber responds, when the circuit of relay R^8 is broken, as previously described. During each energization of relay R^{10} ringing current will be applied to the line as previously described. It will be readily apparent that the ringing relay R^{10} will be inoperative to connect the signaling current to line until the plug P^1 is inserted into the jack J^1 , the plug P^2 inserted into the jack J^2 , and the master switch Q closed. Moreover, the circuit of this relay is controlled directly by the trunk relay and is not dependent upon any intervening apparatus. 20 I make the control relay R^8 self-locking, thus dispensing with a second relay for the performance of this function.

While I have shown these parts thus controlled and operated, I do not wish to be limited thereto, as it will be obvious to those skilled in the art that numerous and extensive departures from the form and details of the apparatus here shown may be made without departing from the spirit of 30 this invention, the same being herein shown solely for the purpose of clearly illustrating specific embodiments of my invention.

I claim:

1. In a telephone system, a plurality of subscribers' lines, a central station circuit, a trunk circuit adapted to be connected to the central station circuit and a called line, a relay in the trunk controlled over the trunk and central station circuit and operated when connection is made between said circuits, a source of signaling current in the trunk, a signaling relay adapted to connect said source in circuit with a called line, a circuit for the signaling relay, a switch in said circuit controlled by the first named relay, a controlling relay in said trunk, a second switch in the circuit of the signaling relay controlled by said controlling relay, a circuit for the controlling relay, a terminal relay controlling the circuit of the controlling relay and a subscriber's relay adapted, when the called subscriber responds, to interrupt the circuit of the controlling relay to disconnect said source of signaling current. 55
2. In a telephone system, a plurality of subscribers' lines, a central station circuit, a trunk circuit adapted to be connected to the central station circuit and to a called line, a source of signaling current in said trunk, a relay for connecting said source to a called line, a circuit for said relay, a controlling relay adapted to operate switch contacts in the signaling relay circuit to complete the same, a circuit for the controlling relay, a terminal relay controlled by the
3. In a telephone system, a plurality of subscribers' lines, a central station circuit, a trunk circuit, a switch to connect the trunk and central station circuit, a second switch to connect the trunk to a called line, a source of signaling current in said trunk, a relay adapted to connect said source in circuit with a subscriber's line, a circuit for said relay, a controlling relay independent of the talking circuit located in the trunk and controlling contacts in said circuit, a trunk relay controlled over the talking circuit controlling contacts in said circuit, said controlling relay under control of said second switch and adapted when said switch is operated to be energized to operate the contacts in the circuit of the signaling relay whereby said signaling relay is inoperative until both said switches are closed. 75
4. In a telephone system, a plurality of subscribers' lines, a central station circuit, a trunk circuit, a switch to connect the trunk and central station circuit, a second switch to connect the trunk to a called line, a source of signaling current in said trunk, a relay adapted to connect said source in circuit with a subscriber's line, a circuit for said relay, a controlling relay independent of the talking circuit located in the trunk and controlling contacts in said circuit, a trunk relay controlled over the talking circuit controlling contacts in said circuit, said controlling relay under control of said second switch and adapted when said switch is operated to be energized to operate the contacts in the circuit of the signaling relay whereby said signaling relay is inoperative until both said switches are closed. 90
5. In a telephone system, a plurality of subscribers' lines, a central station circuit, a trunk circuit, a switch to connect the trunk and central station circuit, a second switch to connect the trunk to a called line, a source of signaling current in said trunk, a relay adapted to connect said source in circuit with a subscriber's line, a circuit for said relay, a controlling relay independent of the talking circuit located in the trunk and controlling contacts in said circuit, a trunk relay controlled over the talking circuit controlling contacts in said circuit, said controlling relay under control of said second switch and adapted when said switch is operated to be energized to operate the contacts in the circuit of the signaling relay whereby said signaling relay is inoperative until both said switches are closed. 95
6. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line and a key in said trunk controlling said relay, said relay being inoperative until both said switching connections are made and said key is operated. 100
7. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line and a key in said trunk controlling said relay, said relay being inoperative until both said switching connections are made and said key is operated. 105
8. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line and a key in said trunk controlling said relay, said relay being inoperative until both said switching connections are made and said key is operated. 110
9. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line and a key in said trunk controlling said relay, said relay being inoperative until both said switching connections are made and said key is operated. 115
10. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line and a key in said trunk controlling said relay, said relay being inoperative until both said switching connections are made and said key is operated. 120
11. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line and a key in said trunk controlling said relay, said relay being inoperative until both said switching connections are made and said key is operated. 125
12. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line and a key in said trunk controlling said relay, said relay being inoperative until both said switching connections are made and said key is operated. 130

6. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line, a circuit for said relay over which the same is energized and a key in said circuit, said circuit controlled by said key and both said switching connections. 5
7. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay adapted to connect said source in circuit with a subscriber's line and a key in said trunk, said relay being controlled by said key and both said switching connections. 10
8. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line, a circuit for said relay, contacts in said circuit controlled by said first named switching means, a key in said trunk controlling contacts in said circuit and other contacts in said circuit controlled by said second 30 named switching means, said signaling relay being inoperative until both said switching means are operated to connect said trunk to said circuits, and said key is operated. 35
9. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line, a circuit for said relay, a trunk relay controlled by said first named switch connections, contacts in said circuit controlled by said trunk circuit, a controlling relay controlled by said second switch connections, other contacts in said signaling relay circuit under control of said controlling relay and a key in said signaling relay circuit, said signaling relay being inoperative to connect said source to line until said trunk is connected to the central station circuit and to the called line and said key is operated. 50
10. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line, a key in said trunk controlling said relay, said relay being inoperative until both said switching connections are made and said key is operated, and means controlled by the called subscriber for causing the disconnection of the source of signaling current from the line. 55
11. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line, a circuit for said relay over which the same is energized, a key in said circuit, said circuit controlled by said key and both said switching connections, and means controlled by the called subscriber for causing the disconnection of the source of signaling current from the line. 60
12. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay adapted to connect said source in circuit with a subscriber's line, a key in said trunk, said relay being controlled by said key and both said switching connections, and means controlled by the called subscriber for causing the disconnection of the source of signaling current from the line. 65
13. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line, a circuit for said relay, contacts in said circuit controlled by said first named switching means, a key in said trunk controlling contacts in said circuit, other contacts in said circuit controlled by said second named switching means, said signaling relay being inoperative until both said switching means are operated to connect said trunk to said circuit, and said key is operated, and means controlled by the called subscriber. 70

for causing the disconnection of the source of signaling current from the line.

14. In a telephone system, a plurality of subscribers' lines, a central station circuit, a 5 trunk circuit, switching means for connecting the central station circuit and the trunk, second switching means for connecting the trunk and the called subscriber's line, a source of signaling current in said trunk, a 10 relay in said trunk adapted to connect said source in circuit with a subscriber's line, a circuit for said relay, a trunk relay controlled by said first named switch connections, contacts in said circuit controlled by 15 said trunk relay, a controlling relay controlled by said second switch connections, other contacts in said signaling relay circuit under control of said controlling relay, a key in said signaling relay circuit, said signaling relay being inoperative to connect said source to line until said trunk is connected to the central station circuit and to the called line and said key is operated, and means controlled by the called subscriber 25 for causing the disconnection of the source of signaling current from the line.

15. In a telephone system, a plurality of subscribers' lines, a central station circuit, a trunk circuit, switching means for connecting said trunk and central circuit, second switching means for connecting said trunk and a called line, a source of signaling current in said trunk circuit, a signaling relay adapted to connect said signaling source in 35 circuit with a called line, a circuit including said signaling relay and a source of current, a plurality of contacts in said circuit, a trunk relay adapted to be operated when the first switching means is operated and controlling contacts in the circuit of the signaling relay, a controlling relay controlling contacts in said circuit, a circuit therefor, said circuit under control of said second switching means and the called subscriber, 45 and a key controlling contacts in said signaling relay circuit.

16. In a telephone system, a plurality of subscribers' lines, a central station circuit, a trunk circuit, switching means for connecting said trunk and central circuit, second switching means for connecting said trunk and a called line, a source of signaling current in said trunk circuit, a signaling relay adapted to connect said signaling source in 50 circuit with a called line, an automatic signaling key associated with said trunk, said ringing relay being controlled by said two switching means and said automatic key.

17. In a telephone system, a plurality of 60 subscribers' lines, a central station circuit, a trunk circuit, switching means for connecting said trunk and central circuit, second switching means for connecting said trunk and a called line, a source of signaling current in said trunk circuit, a signaling relay

adapted to connect said signaling source in circuit with a called line, a circuit for said relay over which the same is energized and an automatic key in said circuit, said circuit controlled by said automatic key and both 70 said switch connections.

18. In a telephone system, a plurality of subscribers' lines, a central station circuit, a trunk circuit, switching means for connecting the central station circuit and the trunk, 75 second switching means for connecting the trunk and the called subscriber's line, a source of signaling current in said trunk, a relay in said trunk adapted to connect said source in circuit with a subscriber's line and 80 an automatic key in said trunk, said relay being controlled by said key and both said switching means.

19. In a telephone system, a plurality of subscribers' lines, a central station circuit, a 85 trunk circuit, switching means for connecting the central station circuit and the trunk, second switching means for connecting the trunk and the called subscriber's line, a source of signaling current in said trunk, a 90 relay in said trunk adapted to connect said source in circuit with a subscriber's line, a circuit for said relay, contacts in said circuit controlled by said first named switching means, an automatic key in said trunk controlling contacts in said circuit and other contacts in said circuit controlled by said second named switching means, said signaling relay being inoperative until both said switching means are operated to connect said 100 trunk to said circuit, and said automatic key is operated.

20. In a telephone system, a plurality of subscribers' lines, a central station circuit, a trunk circuit, switching means for connecting the central station circuit and the trunk, second switching means for connecting the trunk and the called subscriber's line, a source of signaling current in said trunk, a relay in said trunk adapted to connect said source in circuit with a subscriber's line, a circuit for said relay, a trunk relay controlled by said first named switch connections, contacts in said circuit controlled by 115 said trunk relay, a controlling relay controlled by said second switch connections, other contacts in said signaling relay circuit under control of said controlling relay, and an automatic key in said signaling relay circuit, said signaling relay being inoperative to connect said source to line until said trunk is connected to the central station circuit and to the called line and said automatic key is operated.

21. In a telephone system, a plurality of 125 subscribers' lines, a central station circuit, a trunk circuit, switching means for connecting the central station circuit and the trunk, second switching means for connecting the trunk and the called subscriber's line, a 130

source of signaling current in said trunk, a relay in said trunk adapted to connect said source in circuit with a subscriber's line, an automatic key in said trunk controlling said 5 relay, said relay being inoperative until both said switching connections are made and said automatic key is operated, and means controlled by the called subscriber for causing the disconnection of the source of signaling current from the line.

22. In a telephone system, a plurality of subscribers' lines, a central station circuit, a trunk circuit, switching means for connecting the central station circuit and the 15 trunk, second switching means for connecting the trunk and the called subscriber's line, a source of signaling current in said trunk, a relay in said trunk adapted to connect said source in circuit with a subscriber's 20 line, a circuit for said relay over which the same is energized, an automatic key in said circuit, said circuit controlled by said automatic key and both said switching connections, and means controlled by the called 25 subscriber for causing the disconnection of the source of signaling current from the line.

23. In a telephone system, a plurality of subscribers' lines, a central station circuit, a 30 trunk circuit, switching means for connecting the central station circuit and the trunk, second switching means for connecting the trunk and the called subscriber's line, a source of signaling current in said trunk, a 35 relay in said trunk adapted to connect said source in circuit with a subscriber's line, a circuit for said relay, a trunk relay controlled by said first named switch connections, contacts in said circuit controlled by 40 said trunk circuit, a controlling relay controlled by said second switch connections, other contacts in said signaling relay circuit under control of said controlling relay, an automatic key in said signaling relay 45 circuit, said signaling relay being inoperative to connect said source to line until said trunk is connected to the central station circuit and to the called line and said automatic key is operated, and means controlled 50 by the called subscriber for causing the disconnection of the source of signaling current from the line.

24. In a telephone system, the combination of a plurality of telephone lines, central 55 station connecting means, a trunk circuit, means for connecting said central station connecting means and said trunk,

means for connecting the trunk to a called line, a trunk relay controlled by said first means, a source of signaling current for signaling a subscriber on a called line, means including a circuit for connecting said source to a telephone line, contacts in said circuit controlled by said trunk relay and a key in said circuit said last named means being inoperative to connect said signaling source in circuit with the called line until said key and both said first named means are operated.

25. In a telephone system, the combination 70 of a plurality of telephone lines, central station connecting means, a trunk circuit, means for connecting said central station connecting means and said trunk, means for connecting the trunk to a called line, a trunk 75 relay, controlled by said first means, a source of signaling current for signaling a subscriber on a called line, means including a circuit for connecting said source to a telephone line, contacts in said circuit operated 80 by said trunk relay, a key in said circuit, said last named means being inoperative to connect said source to a called line until said key and both said first named means are operated and a subscriber's relay adapted 85 to interrupt the said circuit when the called subscriber responds.

26. In a telephone system, a central station, telephone lines terminating thereat, a connecting circuit thereat, a subcentral station, 90 telephone lines terminating thereat, a trunk circuit connecting said central stations, switching means for connecting the central station connecting means and the trunk circuit, switching means for connecting the 95 trunk circuit to a called line, a trunk relay controlled over the central station end of the trunk, a source of signaling current adapted to be connected up to signal a called substation, means controlling the connection of 100 said source, a circuit for said means, a switch in said circuit directly controlled by the trunk relay, a terminal relay controlled by the trunk-line switching means, a self-locking relay controlled by said terminal relay 105 and a switch in the circuit of the signaling source controlling means governed by the self-locking relay.

In testimony whereof I affix my signature in presence of two witnesses.

FRANK B. ALLEN.

Witnesses:

C. B. HARLOW,
F. O. RICHEY.
